UNITED STATES PATENT OFFICE.

JOHN R. TOWNSEND, OF CHICAGO, ILLINOIS.

AIR-BREAK SWITCH.

1,275,326.

Specification of Letters Patent. Patented Aug. 13, 1918.

Application filed November 26, 1915. Serial No. 63,659.

To all whom it may concern:

Be it known that I, JOHN R. TOWNSEND, a citizen of the United States, residing at Chicago, in the county of Cook and State of Illinois, have invented certain new and useful Improvements in Air-Break Switches, of which the following is a specification.

My invention relates to air-break switches, and refers particularly to switches which 10 are used for opening the circuits of high-tension transmission lines.

The air-break switches of the class to which my invention belongs are ordinarily mounted on the tops of poles or towers, 15 which carry the transmission lines. In the usual 3-phase system three conductors lead to an air-break switch and three conductors lead from this switch, the switch itself having three sets of contacts which serve to 20 bridge the respective conductors and make electrical connection therebetween. As the current transmitted over a high-tension system is often in excess of 60,000 volts, it will be apparent that unusual precautions must 25 be taken in connection with the construction of air-break switches to prevent destructive and dangerous arcing when the switch is opened, thereby interrupting the circuit.

It is the object of my invention to open 30 a high-tension circuit quickly and surely without the formation of a destructive arc and without danger of enabling the current to "strike" from one of the parallel conductors or phases to another, thus causing short-circuiting of the system.

It is a further object of my invention to 35 provide auxiliary contacts, which remain in engagement with each other after the main contacts have been separated from each 40 other, so that all of the arcing will take place at the auxiliary contacts, which are of relatively cheap material, and which, owing to the construction of my improved switch, are quickly separated from each other by a 45 wide gap on opening of the switch, thereby causing the rapid and certain breaking of the arc.

A still further object of my invention resides in constructing the two operating 50 halves of the switch so that the parts rotate in a vertical plane and in opposite directions at the same rate of speed, mechanism also being provided so that abrupt and sudden movement of the switch at or near its 55 closed and full open positions is avoided, thus doing away with danger of injuring the

switch on account of careless handling under the stress of excitement or for other cause.

A still further object of my invention resides in the provision of a protector for the main contacts so that the operation of the latter may not be interfered with by accumulations of sleet or ice on the contacts. The protector is so constructed that it serves 65 to cover the contacts when the latter are both in closed and open positions.

A still further object of my invention resides in the means for connecting the switch with the conductors which it serves to bridge 70 so that there is no possibility of any loose or flexible conductor coming in contact with a grounded framework or other insulated parts, which might cause injury to life or property.

These and other advantages of my invention will be more readily understood by reference to the accompanying drawings, in which—

Figure 1 is an end elevation of my improved switch, showing its operating mechanism connected therewith;

Fig. 2 is a plan of the switch shown in Fig. 1;

Fig. 3 is a fragmentary sectional view 85 taken on the line 3—3 of Fig. 2, and showing the drag link used to connect the two sides of the switch;

Fig. 4 is a vertical section through one of the cross-pieces, showing one of the toggle 90 guides attached thereto;

Fig. 5 is an enlarged section through the auxiliary contacts, showing a plan of the contact guide; and

Fig. 6 is an enlarged plan of the main contacts and sleet protector, a portion of the latter being broken away.

In Fig. 2 I have shown my improved switch as constructed for a 3-wire system, the conductors 10 leading to the insulators 100 11, which, in turn, are anchored to the stringers 12. Although I have shown three pairs of conductors, it will be evident that any other suitable number could be employed, it being only necessary to duplicate 105 the various parts which are associated with each pair of conductors which are bridged or electrically connected by means of the switch.

The stringers 12 are supported on the 110 arms 13, which, in turn, are carried by the poles 14. These stringers are additionally

braced by means of the cross-braces 15. Resting on the stringers 12 are the channel irons 16, which are provided at their ends with the bearings 17, which serve to support the two shafts 18. These shafts extend the entire length of the stringers 12.

On each of the shafts 18 is mounted the insulator support 19 carrying a petticoat insulator 20. Each of the insulators 20 carries at its outer end the bracket 21, which, in turn, carries the contact rod 22, of copper, brass, or other suitable conducting material. As most clearly shown in Fig. 6, one of the contact rods 22 has attached thereto the contact blade 23, whereas the opposite contact rod 22 carries the spring contacts 24, 24, between which the contact blade 23 is adapted to be inserted and form snug contact therewith. By using the form of contacts which I have just mentioned severe jar is avoided when the contact blade 23 is brought into connection with the spring contacts 24.

Each of the contact rods 22 has a flexible steel auxiliary contact 25 attached thereto, one of these auxiliary contacts carrying near its upper end the guiding V 26, by means of which electrical connection between the two auxiliary contacts 25, 25 is insured when the switch is in closed position.

A link 27 is pivotally connected to the outer end of each of the contact rods 22, and is, in turn, connected at its outer end with a link 28 which has its opposite end pivotally attached to the bracket 29 carried by the conductor 10.

As clearly shown in Figs. 1 and 6, the contact blade 23 and the spring contacts 24 are protected, respectively, by the housing 30 closed at its top and sides. When the switch is in closed position, as indicated in full lines in Fig. 1, the two housings 30 are brought into contact with each other and form a tight joint on their inner ends so that the main contacts, consisting of the blades 23 and the spring contacts 24, are effectually protected from the action of snow, sleet, rain, or the like. In order to carry off water the housings 30 on their tops preferably slope slightly from their inner to their outer edges. Each of the housings 30 is pivotally connected to the corresponding contact rod 22 by engagement of the screws 31 with the cross-member 32 carried by the end of the contact rod 22. A link 33 serves to connect each of the housings 30 with a bracket 34, which is pivotally mounted on the link 27.

In order to provide electrical connection between each pair of conductors 10 in the same line, each of the links 28 is connected with the corresponding conductor 10 through the flexible conductor 35, which, on one end, is suitably connected to the con-

ductor 10 and on the other end to the link 28, which is constructed of brass, copper, or other suitable conducting material. Similarly, the flexible conductor 36 serves to connect the link 28 with the link 27, and the conductor 37 connects the link 27 with the contact rod 22.

I will next pass to a description of the actuating mechanism for the switch. This actuating mechanism is preferably located near one of the poles 14, as clearly shown in Figs. 1 and 2. The arms 38, rigidly mounted on the shafts 18, are connected by the toggle 39, which consists of the two rods 40 pivotally connected with each other at 41. These two rods 40 operate within the guides 42, which are suitably attached to one of the channel irons 16, as clearly shown in Figs. 2 and 4. A drag link 43 having the pivotally connected arms 44 mounted on the shafts 18 serves to insure that on rotation of one of the shafts 18 in one direction the other shaft will be rotated in the opposite direction at the same rate of speed.

Pivoted to the toggle 39 at the 90 pivotal point 41 is the link 45, which leads to the end of the arm 46 of the bell crank lever 47, which is pivotally mounted at the point 48 on the plate 49, which is carried by the pole 14. To the arm 50 of the bell crank lever 47 is attached the link 51, and to the arm 52 is attached the link 53. The lower ends of the links 51 and 53 are attached to the respective ends of the lever 54 pivotally mounted at 55 on the plate 56 100 carried by the pole 14. Each of the links 51 and 53 preferably has therein an insulating section 57 to act as a safeguard to prevent the passage of high-tension current to the operating handle, which will next be 105 described. The operating handle 58 is attached to the lever 54, and when this operating handle is swung from the position indicated in full lines in Fig. 1 to the position indicated in dotted lines, the lever 54 is rotated on its pivot 55 into the position shown in dotted lines. The pole 14 carries a cross-arm 59 so that when the operating handle 58 is swung from one position to another a 115 staple, or similar device, may be inserted through the aperture 60 in the handle 58 and passed into the cross-arm 59 so that the handle 58 will be held in the position to which it has been moved.

Having thus described the various parts 120 which are used in connection with my improved switch, the operation of the same may now be readily understood:

When the switch is in closed position the various parts are as shown in full lines in 125 Fig. 1. The current passes from one of the main conductors 10 through the flexible conductor 35, thence through the link 28, flexible conductor 36, link 27, flexible conductor 37, and contact rod 22, through the contact 130

blade 23 and spring contacts 24, to the opposite contact rod 22, flexible conductor 37, link 27, flexible conductor 36, link 28, and flexible conductor 35, to the main conductor 10 on the side of the switch opposite to the conductor 10 first mentioned. It will thus be evident that the circuit between the conductors 10 of the same line is thus closed. When it is desired to open the switch, the handle 58 is moved to the position shown in dotted lines in Fig. 1. Through the instrumentality of the lever 54 and the links 51 and 53, the bell crank lever 47 is moved into the position shown in dotted lines, so that the arm 46 is brought into engagement with the stop 61, the arm 52 having been in engagement with the stop 62 when the bell crank lever was in the position indicated in full lines. As the movement of the handle 58 and the bell crank lever 47 begins to take place, the link 45 is moved upwardly, and causes the pivotal point 41 of the toggle 39 to be carried upwardly until the link 45 and the arm 46 are brought into the same axis. This toggle 39 causes the arms 38 to be moved inwardly so that the shafts 18 are rotated in opposite directions. It will be evident that as the pivotal point 41 of the toggle 39 first begins to move upwardly the movement communicated through the arms 38 to the shafts 18 will be relatively slow, but will become more rapid as the two rods 40 of the toggle become disposed at a more acute angle to each other. On the other hand, as the arm 46 of the bell crank lever 47 approaches its vertical position, and thereby a dead center, the upper end of the link 45, and, therefore, the pivotal point 41, will travel upwardly at a slower rate (assuming a uniform rate of movement of the operating handle 58), this upward movement of the point 41 gradually decreasing in velocity until the link 45 and the arm 46 are brought into the same axis, whereupon further rotation of the shafts 18 stops. The gradual cessation of movement near the extreme open position of the switch, and a similar action taking place when the switch is closed, is a feature of great advantage, inasmuch as it effectually prevents undue strains caused by severe shocks or jars which would otherwise take place if the switch were carelessly or unskillfully operated. According to the construction which I have just described, no matter how violently the operating handle 58 is moved from one extreme position to the other the switch itself is always opened or closed, as the case may be, without jar or shock.

As the shafts 18 are rotated in the manner just described, the movement of the two shafts is kept in synchronism by the action of the drag link 43. The insulators 20 are moved outwardly into the dotted positions. As this movement takes place

the contact blade 23 is withdrawn from the spring contacts 24 so that the passage of current through these main contacts is interrupted. After the main contacts have been separated, however, the auxiliary spring contacts 25, which gradually straighten out as the insulators 20 are moved outwardly, are still maintained in contact with each other, so that the current passes from one contact rod 22 to the other through these auxiliary contacts 25. The engagement between the two auxiliary contacts 25 continues until the point 41 of the toggle 39 has traveled approximately one-third of its total distance of travel in a vertical plane. By this time the shafts 18 are rotating at a considerable and gradually increasing rate of speed. The upper ends of the auxiliary contacts 25 are now quickly separated from each other, and the parts are thereafter brought into the position shown in dotted lines. It will be evident that the arc-breaking distance between the ends of the two auxiliary contacts 25 is very great in proportion to the movement of the switch as a whole, and an arc is thus quickly and effectively broken not only on account of the great distance by which the auxiliary contacts are separated from each other, but also on account of the fact that when the separation takes place the movement of the auxiliary contacts in opposite directions is very rapid.

As the switch is moved from closed to open position, it will be evident that the link 33 pivotally attached to the protector casing 30 and to the link 27 will maintain the protector 35 in position so that the latter covers the contact blade 23, or the spring contacts 24, as the case may be, when the switch is in its full open position. In this way water, snow, sleet, and the like, are prevented from accumulating on the switch blade or spring contacts.

When it is desired to close the switch the operating handle 58 is, of course, moved from the position shown in dotted lines to that shown in full lines in Fig. 1. The auxiliary contacts 25 first engage each other so that any arcing which results takes place at these auxiliary contacts. The contact blade 23 is thereafter brought into engagement with the spring contacts 24, and the normal passage of current, as previously described, takes place. The engagement of the contact blade 23 with the spring contacts 24 is very efficient, while at the same time there is no violent shock or jar connected with this operation. This feature, taken in conjunction with the gradual decrease in the rapidity of rotation of the shafts 18 as the full open and full closed positions of the switch are approached, greatly relieves the strain on the insulators 20, and I have found by practical experience that the breakage of

the insulators is thus greatly decreased over the breakage which occurs in prior forms of air-break switches.

It will be apparent to those skilled in the art that many changes could be made in the construction of the parts which I have described without departing from the spirit or scope of my invention, as defined in the appended claims.

10. What I claim is:

1. In an electric switch, the combination of a pair of main contact members adapted to engage each other, means for separating said contact members from each other, a pair 15 of auxiliary spring contact members each of which is carried by one of said main contact members, said auxiliary contact members adapted to engage each other during the engagement of said main contact members 20 and to be separated from each other only after said main contact members have been separated from each other, and a V-shaped guiding member carried by one of said auxiliary contact members, whereby the engagement of the other auxiliary contact member with said first-mentioned auxiliary contact member is insured.

2. In an electric switch, the combination of a shaft, means for rotating said shaft, an 30 insulator carried by said shaft, a contact member carried by said insulator, said contact member having an end adapted to engage a companion contact member, a protector housing carried by and above the 35 engaging end of said contact member, and means for maintaining said housing in covering position above said end during rotation of said shaft in moving said switch from closed to open position, whereby said 40 end is covered in every position at all times.

3. In an electric switch, the combination of a shaft, means for rotating said shaft, an insulator carried by said shaft, a contact member carried by said insulator, said contact member having an end adapted to engage a companion contact member, a link 45 pivotally connected with said contact member, a protector housing above the engaging end of said contact member and pivotally connected thereto, and means extending from said housing to said link for maintaining said housing in position above said engaging end of said contact member during rotation of said shaft in moving said switch 50 from closed to open position.

4. In an electric switch, the combination of a pair of parallel shafts, means for simultaneously rotating said shafts in opposite directions, an insulator carried by each 60 of said shafts, a contact member carried by each of said insulators, said contact members having ends adapted to engage each other, a protector housing above each of said engaging ends and movable with said contact members, and means for maintaining 65

said housings in protecting position above said engaging ends during rotation of said shafts in moving said switch from closed to open position.

5. In an electric switch, the combination 70 of a pair of parallel shafts, a contact member carried by each of said shafts, said contact members adapted to be brought into engagement with each other when said switch is in closed position, a protector housing carried by each of said contact members, and means for simultaneously rotating said shafts in opposite directions from one predetermined position of said shafts to another at a rate of speed gradually increasing from 80 the starting point to substantially the mid-point of the path of travel of said shafts and at a rate of speed gradually decreasing from substantially the mid-point to the end of said path of travel. 75

6. In an electric switch, the combination 85 of a pair of parallel shafts, a contact member carried by each of said shafts, said contact members adapted to be brought into engagement with each other when said switch 90 is in closed position, means for simultaneously rotating said shafts in opposite directions from one predetermined position of said shafts to another at a rate of speed gradually increasing from the starting point 95 to substantially the mid-point of the path of travel of said shafts and at a rate of speed gradually decreasing from substantially the mid-point to the end of said path of travel, and means for rotating said shafts 100 synchronously.

7. In an electric switch the combination 105 of a pair of parallel shafts, a contact member carried by each of said shafts, said contact members adapted to engage each other when said switch is in closed position, a toggle having a pair of arms pivotally connected with each other and forming a substantially straight line with each other when said switch is in closed position, and means 110 for moving the pivotal point of connection of said toggle arms, whereby said shafts will be rotated in opposite directions at a gradually increasing rate of speed and said contact members will be separated from each 115 other.

8. In an electric switch, the combination 120 of a pair of parallel shafts, a contact member carried by each of said shafts, said contact members adapted to engage each other when said switch is in closed position, a toggle having a pair of arms pivotally connected with each other and forming a substantially straight line with each other when said switch is in closed position, a bell 125 crank lever, a link extending from the pivotal point of connection of said toggle arms to one arm of said bell crank lever, said arm and said link adapted to be brought into substantially a straight line when the 130

switch is in open position, and means for actuating said bell crank lever.

9. In an electric switch, the combination of a pair of parallel shafts, a contact member carried by each of said shafts, said contact members adapted to engage each other when said switch is in closed position, a toggle having a pair of arms pivotally connected with each other and forming a substantially straight line with each other when said switch is in closed position, a bell crank lever, a link extending from

the pivoted point of connection of said toggle arms to one arm of said bell crank lever, said arm and said link adapted to be 15 brought into substantially a straight line when the switch is in open position, means for actuating said bell crank lever, and a drag link connecting said shafts, whereby the latter will be moved synchronously. 20

In witness whereof I hereunto subscribe my name this 23rd day of November, A. D. 1915.

JOHN R. TOWNSEND.

It is hereby certified that in Letters Patent No. 1,275,326, granted August 13, 1918, upon the application of John R. Townsend, of Chicago, Illinois, for an improvement in "Air-Break Switches," errors appear in the printed specification requiring correction as follows: Page 4, strike out lines 11 to 27 and 86 to 116, comprising claims 1, 6, and 7; renumber claims 2, 3, 4, 5, 8, and 9 as 1, 2, 3, 4, 5, and 6; and that the said Letters Patent should be read with these corrections therein that the same may conform to the record of the case in the Patent Office.

Signed and sealed this 8th day of October, A. D., 1918.

[SEAL.]

R. F. WHITEHEAD,

Acting Commissioner of Patents.

Cl. 175—282.
